DOOR CLOSER AND STOP

John A. Wagner, St. Petersburg, Fla.

Application September 4, 1952, Serial No. 307,796

4 Claims. (Cl. 16—65)

This invention relates to door checks of the type used for retaining doors in open, partly open and closed positions and also for closing doors, and in particular a casing mounted on a door frame with an arm extended from the casing and having a pin positioned in a slot of a bracket on a door and in which springs in the casing urge traveling rollers into engagement with notches whereby the door may be retained in the open or partly open position, or may be closed.

The purpose of this invention is to provide a door check with which a door is closed with a slow easy movement and which may also be used to retain a door in an open or partly open position.

Various types of door closing devices and also devices for retaining doors in open positions have been provided. However, in the conventional pressure actuated device it is necessary for a mechanic to set the parts continuously and where such devices are used in localities where servicing is difficult the operation thereof is not successful. With this thought in mind this invention contemplates a door check and closer in which the parts are comparatively rugged and wherein it is only necessary to remove a cap and nut to clean or replace parts.

The object of this invention is, therefore, to provide means for forming a door closer and stop whereby the stop may be serviced by an unskilled mechanic.

Another object of the invention is to provide an improved door closer and stop in which the device is mounted on a door frame with an arm extended therefrom slidably connected to a door hinged in the frame and in which the device may be installed without making changes in the door or frame.

A further object of the invention is to provide an improved door closer and stop which is of a simple and economical construction.

With these and other objects and advantages in view the invention embodies a cylindrical housing having an arm extended from the lower end of a vertically positioned shaft journaled in the housing, a roller on the end of the arm adapted to travel in a slot in a bracket on a door and rollers in the housing resiliently held by a spring in spaced notches of the housing, and wherein the arm is actuated by another spring also positioned in the housing.

Other features and advantages of the invention will appear from the following description taken in connection with the drawings, wherein:

Figure 1 is an elevational view showing the upper part of a door with the improved door closer and door stop mounted on the door and frame thereof.

Figure 2 is a vertical section through the housing of the improved door closer and stop with the parts shown in section.

Figure 3 is a sectional plan through the upper part of the housing taken on line 3—3 of Fig. 2.

Figure 4 is also a sectional plan through the upper part of the housing taken on line 4—4 of Fig. 2.

2

Figure 5 is a detail showing a section taken on line 5—5 of Fig. 2 illustrating a bracket adapted to be positioned on a door and providing a guide for the extended end of an arm carried by a shaft in the housing.

5 Figure 6 is a detail taken on line 6—6 of Fig. 1 looking upwardly and showing the housing mounted on a door frame with the guide bracket on the door, and in which the parts are shown on an enlarged scale.

10 Figure 7 is an end elevational view also showing the device mounted on a door frame and with the guide bracket on a door in the frame.

Referring now to the drawings wherein like reference characters denote corresponding parts the improved door closer or stop of this invention includes a housing 10, a disc 11 mounted on the upper end of the housing, a collar 12 rotatably mounted on the disc 11, a disc 13 mounted on the lower end of the housing, a shaft 14 positioned in the center of the housing, a cylinder 15 slidably mounted on the shaft 14 and having rollers 16 and 17 journaled in arms 18 and 19, respectively, a spring 20 for urging the rollers against the upper end of the collar 12, a spring 21 for rotating the shaft 14 and an arm 22 carried on the lower end of the shaft and positioned whereby a sleeve 23 on a pin 24 extends through a slot 25 in an angle bar forming a guide bracket 26.

In the design shown the housing 10 is cylindrical and is mounted on a door frame as indicated by the numeral 27 with flanges 28 and 29 which are provided with openings 30 and 31 for receiving screws 32 which secure the housing to the frame.

25 The lower end of the housing 10 is provided with an annular recess 33 in which a flange 34 of the disc 13 is positioned and the disc is secured in position by screws 35 extended through the flange and threaded into the housing. The disc 13 extends into an annular slot formed by a recess 36 in a disc 37 fixedly mounted on the shaft 14 and a complementary annular recess 38 in the face of a flange 39 which is secured to the shaft 14 with a screw 40. Gaskets 41 and 42 are provided between the disc 30 13 and disc 37 and flange 39 for sealing the lower end of the housing. The disc 37 is provided with projections 43 in which openings 44 that receive the end of the spring 21 are positioned.

40 The upper end of the spring 21 is secured in openings 45 of projections 46 which extend downwardly from the disc 11 and a flange 47 on the peripheral edge of the disc is positioned in a recess 48 in the upper end of the housing. The disc 11 is secured in position by screws 49 which extend through the flange 47 and into the housing.

45 The upper surface of the disc 11 is also provided with an annular recess, as indicated by the numeral 50 and a lip 51 extended from the outer edge of the collar 12 extends into said recess. The collar 12 is secured in adjusted positions by bolts 52 which extend through slots 55 53 and 54 in a web 55 of the collar, the bolts being threaded into the disc 11.

50 With the parts arranged in this manner the collar 12 may be set whereby notches 56 in the upper edge of the wall thereof are positioned to stop and hold the door 60 in the full open position or in intermediate positions between the full open and closed positions. The collar 12 may be provided with one set of notches, such as the notches 56 whereby a door may be retained in a full open position and also in a partly open position, upon resetting the collar. The upper end of the wall of the collar is provided with arcuate surfaces as indicated by the numerals 57 and 58 which lead to the notches whereby the door travels with a smooth easy movement.

65 The rollers 16 and 17 are journaled by pins 59 and 60 in recesses 61 and 62, in the end of the arms 18 and 19 respectively of the cylinder 15 and the spring

20, positioned in the cylinder and held by a nut 63 and washer 64 urges the rollers against the end surface of the wall of the collar 12 whereby the rollers are secured in the notches. The peripheral surface of the collar 12 is also provided with an annular groove 65 in which a bead 66 on the edge of a cap 67 extends whereby the cap may be snapped over the collar to provide a closure for the upper end of the housing. The cap may readily be removed when it is desired to adjust the position of the nut 63 to regulate the tension on the roller or when it is desired to adjust the position of the collar 12 to change the position of the door.

The arm 22 is provided with a hub 68 at one end and the hub, which is provided with a square opening 69 to receive the square end of the shaft 14 is secured on the shaft with a set screw 70. A hub 71 on the opposite end of the arm is positioned to provide mounting means for a pin 24 on which the sleeve 23 is journaled and the pin 24 is secured in the hub 71 with a set screw 72. The sleeve 23 is secured on the pin 24 with a washer 73 and the washer is held in position by a screw 74.

The bracket 26 is mounted on the face of a door with screws, as indicated by the numeral 75, or by other suitable means.

With the parts assembled in this manner and with the axis of the shaft 14 in alignment with the pins of hinges 76 by which a door, as indicated by the numeral 77 is secured in the frame 27 and with the guide bracket 26 secured to the upper edge of the door the spring 21 will wind as the door is opened whereby as soon as the door is released the spring will urge the door toward the closed position.

With the rollers 16 and 17 traveling on the upper edge of the collar 12 and resiliently held against the collar by the spring 20 friction is provided that controls the movement of the door and as the roller drops into notches the movement of the door is arrested so that it may be stopped in different positions by adjusting the positions of the notches.

It will be understood that modifications, within the scope of the appended claims, may be made in the design and arrangement of the parts without departing from the spirit of the invention.

What is claimed is:

1. A door closer comprising a housing adapted to be positioned on a door frame, a bracket having an elongated slot therein adapted to be positioned on a door, a shaft positioned in the housing and extended from one end thereof, an arm carried by the shaft, a pin carried by the arm and positioned to extend through the slot of the bracket, a disc in the lower end of the housing on the shaft and adapted to rotate with the shaft, a second disc in the upper end of the housing fixed thereto, resilient means for rotating the shaft fixed at one end to the disc in the lower end of the housing and at its opposite end to the disc in the upper end of the housing, means mounted on the shaft for frictionally controlling the rotation of the shaft, and means in said friction controlling means for holding the shaft in various positions to which it is turned by opening the door.

2. A door closer comprising a housing adapted to be positioned on a door frame, a bracket having an elongated slot therein adapted to be positioned on a door, a shaft positioned in the housing and extended from one end thereof, an arm carried by the shaft, a pin having a sleeve thereon carried by the arm and positioned to extend through the slot of the bracket, a disc in the lower end of the housing adapted to rotate with the shaft, a second disc in the upper end of the housing fixed thereto, a spring in the housing with one end connected to the second disc fixed to the housing and the other to the first disc on the shaft whereby opening movement of a door on which the bracket is positioned winds the spring,

said housing having a section with notches therein on the upper end, a cylinder carried by said shaft, arms on the upper edge of the cylinder, rollers rotatably mounted on the outer ends of the arms on the cylinder carried by the shaft and positioned to engage the notches of the housing for retaining the shaft in different positions, and resilient means on said shaft within said cylinder for urging the rollers against the end of the housing and into said notches.

3. A door closer comprising a housing adapted to be positioned on a door frame, a bracket having an elongated slot therein adapted to be positioned on a door, a shaft positioned in the housing and extended from one end thereof, an arm carried by the shaft, a pin having a sleeve thereon carried by the arm and positioned to extend through the slot of the bracket, a disc in the lower end of the housing adapted to rotate with the shaft, a second disc in the upper end of the housing fixed thereto, a spring in the housing about the shaft with one end connected to the disc in the upper end of the housing and the other end connected to the disc adapted to rotate with the shaft whereby opening movement of a door on which the bracket is positioned winds the spring, said housing having a section with notches therein on the upper end, a cylinder carried by said shaft, outwardly extending arms on the upper edge of the cylinder, rollers rotatably mounted on the outer ends of the arms on the cylinder carried by the shaft and positioned to engage the notches of the housing for retaining the shaft in different positions, resilient means on said shaft within said cylinder for urging the rollers against the end of the housing and into said notches, means adjusting the positions of the notches of the housing and means adjusting the tension of the resilient means for urging the rollers toward the housing and into the notches.

4. In a door closer, the combination with a vertically positioned cylindrical housing having flanges extended from one side, said housing positioned on a door frame with fastening elements extended through the flanges thereof and into the frame, an elongated guide bracket having an elongated slot therein positioned on a door positioned on said frame, a vertically disposed shaft extended through the housing, an arm carried by the lower end of the shaft, a pin having a sleeve journaled thereon extended downwardly from the extended end of the arm and positioned to travel in the elongated slot of the bracket, a cylinder having arms extended from one end mounted on the shaft, a collar having notches in the end surface positioned on the upper end of the housing, rollers journaled in the arms of the cylinder and positioned to travel on the end surface of said collar, a spring positioned on the shaft and extended into the cylinder, a nut threaded on the shaft for maintaining tension in the spring whereby the spring acting through the cylinder urges the rollers against the end surface of the collar of the housing, a disc in the upper end of the housing fixed thereto, a second disc in the lower end of the housing carried by the shaft and adapted to rotate with the shaft, and a spring in the housing with one end attached to the disc fixed to the housing and the other to the disc carried by the shaft for rotating the shaft to urge the door to a closed position in the frame.
